MACHINE FOR PLATING ARTICLES

Carl G. Olson, Chicago, Ill., assignor to Illinois
Tool Works, Chicago, Ill., a corporation of Illi-
nois

Application December 4, 1937, Serial No. 178,054

7 Claims. (Cl. 204—199)

The present invention relates to an apparatus for plating articles and more particularly to a device, as well as process of operation, for continuously applying a predetermined thin coating to preformed articles.

It is an object of the present invention to provide a machine for applying a plated coating to preselected sections only, of preformed articles.

The present invention more particularly comprehends the provision of an improved apparatus for applying a coating, such as a plating of dissimilar metal, to a selected portion of the surface of an article.

One article of manufacture, the production of which may be greatly facilitated as the result of a practical application of the present invention, is disclosed in my co-pending application, Serial No. 110,523, filed October 12, 1936, and comprises a thread cutting or tapping fastener, the entering end only of which is provided with a coating of a material dissimilar to the material forming the body of the fastener in order to facilitate application thereof to the work. It is normally desirable that the exposed portions of such fasteners retain their unchanged character and appearance after being coated so as to provide the desired uniform exterior effect in combination with the work material, and for this and other reasons it is important that no plating be applied adjacent the head portions.

It is, accordingly, an important object of the present invention to provide a machine for continuously arranging fasteners, as well as like articles, in proper relationship with respect to the plating agency to cause plating to take place on a predetermined portion thereof, and to cause said articles to be so maintained for a controlled period of time and under the proper conditions to produce a coating or plating of the desired extent and character.

An additional object of the present invention is to provide an improved apparatus for electro-plating fasteners uniformly on the entering end thereof without varying the character or appearance of the head portions.

Other objects are to provide an apparatus adapted for continuously suspending fasteners with their entering portions only in plating relationship to an electro-plating bath and moving them in a predetermined path through the plating bath while applying an electric current for causing a deposition of the coating on the immersed parts, the operation taking place in timed relationship to the distance travelled and the fasteners being disconnected automatically from the

electrical current after plating has been accomplished; to provide a relatively simple, improved means for carrying out the above plating method which is formed of a relatively small number of parts arranged so as to be reliable in operation and provide infrequent necessity for repair and adjustment; and to provide a machine for continuously immersing thread-forming fasteners in an electro-plating bath for depositing an electro-plated coating on a predetermined portion of the length thereof only wherein the level of the bath is at all times maintained substantially constant.

Numerous other objects and advantages will more fully appear during the course and progress of the following specification.

Figure 1 is a plan view of a machine constructed in accordance with the present invention.

Figure 2 is a sectional elevation taken on the line 2—2 in Figure 1.

Figure 3 is a detail sectional elevation taken on the line 3—3 in Figure 1.

Figure 4 is a detail plan view taken on the line 4—4 in Figure 3.

Figure 5 is a sectional elevation taken on the line 5—5 in Figure 3.

Figure 6 is a sectional elevation taken on the line 6—6 in Figure 1.

Figure 7 is a perspective view of the screw ejector.

Figure 8 is a perspective view of an anode basket.

Figure 9 is a sectional elevation taken on the line 9—9 in Figure 4.

Figure 10 is a view the same as Figure 9, but showing the method of positioning a slightly different type of fastener.

The machine, shown in the drawings for the purpose of illustrating the present invention, comprises generally a frame 10 on which is mounted a screw feeding hopper 12 which supplies the inclined conveyor or chute 14, and a rotary carrier 16 for supporting and positioning the thread-forming fasteners with proper respect to the plating bath 18 so that the ends thereof will be given the desired metallic coating. The screws or fasteners are dumped into the hopper 12 from which they are moved or fed down the conveyor or guide chute 14, at the end of which they are individually deposited in spaces provided therefor about the periphery of the rotatable carrier 16. The rotatable carrier grasps the individual screws with a means which electrically connects them in the electro-plating circuit and supports the lower portions thereof in proper re-

lationship to the bath for causing the initiation of the plating on the predetermined end portions thereof and is then moved rotationally in substantially timed relation to the distance travelled in each rotation to convey the screws through the bath. Substantially at the termination of one cycle of rotation, the plated articles are automatically ejected from the carrier and subsequently retrieved in the finished form.

More specifically, the supporting frame of the machine, as shown in the drawings, comprises four legs 20 formed of angle iron spaced transversely by the frame members 22 and longitudinally by the upper frame members 24 and 25 and the lower frame members 26. The frame may be provided with a plurality of foot portions, preferably formed by short sections 28 of angle iron, to assist in supporting and positioning the assembly. The forward, longitudinally extending frame member 25, as viewed in Figure 2, is divided adjacent its central portion by downwardly extending angle members 30 and 32 which are secured to the adjacent bottom ends by the angle member 34. This longitudinally extending frame member is thus relieved downwardly to form a U-shaped support for a portion of the plating bath, as will hereinafter appear.

As shown in Figures 1 and 2, the screw-feeding mechanism and hopper for the fasteners to be plated is rigidly mounted between the longitudinally extending frame members 24 and 25 adjacent one end of the structure and comprises a hopper 36 having an opening at the top into which the fasteners are initially introduced. Slidably mounted in suitable guideways formed in the hopper feeding device is a reciprocating plate 38 which, as it moves upwardly, picks up the fasteners from the mass thereof in the hopper and tends to drop and arrange them with proper respect to the conveyor or chute 14.

Vertical reciprocation of the plate 38 is maintained by means of the link 40 which is pivotally connected thereto and to an eccentric portion of the rotating crank member 42 driven by means which will hereinafter be described more in detail. This latter member comprises more particularly a pair of spaced bars 44 and 46. The bar 46 is mounted in brackets (not shown) which are a part of the hopper 36. The bar 44 is also mounted upon the same supporting brackets in any, conventional manner to permit adjustment toward and from the bar 46 to accommodate screws having shanks of various sizes. A cover plate 48 overlies the space formed between the bars 44 and 46 and is secured thereto by means of the straps 50 in any convenient manner to permit a vertical adjustment to accommodate screws having heads of different height. The screws fed in the hopper are, accordingly, arranged between the bars 44 and 46, as clearly shown in Figures 2, 3 and 4, with the lower face of the head portion residing upon the top face of the two aforementioned bars and, in this position, they are permitted to slide down the inclined plane formed thereby in a continuous line to a point or station opposite the periphery of the rotatable carrier 16.

The electro-plating bath 18 comprises a tank, more completely shown in Figures 1 and 2, and throughout its main portion being of substantially annular form and being defined by outer and inner, annular wall sections 52 and 54, respectively, closed by the bottom wall 56. Attention is directed to the fact that the tank is distorted or enlarged outwardly adjacent the front and right-hand portions, as viewed in Figure 2, and this

section is further provided with a deepened or well section for accumulating and retrieving the plated articles. This enlarged portion of the tank is defined by upstanding walls 58 and 60 which are integral with the extended sides of the wall 52. The bottom wall 56, extended to form a bottom for this enlarged portion of the tank, is interrupted by the deepened or well portion 62. This deepened or well portion, closed at the bottom by the lower wall 64, is, in the embodiment 10 shown, rectangular in shape although it will be obvious from the instant disclosure that the form thereof may be varied considerably within wide limits.

The electro-plating tank is further stiffened 15 and supported by means of an angle member 66 which is bent to conform with and to completely embrace the outer periphery thereof, as shown in Figures 1 and 2. The purpose of this tank being to contain the electrolyte or plating solution from which the electro-plating of the fasteners is carried out, means is provided for adding and withdrawing the solution therefrom, as well as for circulating the solution, if desired, and maintaining at all times a preferred level of 20 liquid therein. This means comprises a drain cock 68 mounted in the lower wall 64 of the well portion 62. An auxiliary supply tank 70 is further connected to the plating bath by means of the return conduit 72 and the pump 74. The pump 30 may be driven by means which will be hereinafter defined in detail and may be arranged to continuously supply liquid from the tank 70 to the bath.

The means for maintaining a constant level of 35 liquid in the bath comprises an upstanding overflow pipe 76 disclosed in Figures 1 and 2, and provided with a threaded sleeve 78 so that the effective overflow height of this member may be readily adjusted at any time to maintain the preferred level of plating solution in the bath. Attention is directed to the fact that the overflow pipe 76 discharges into the reserve tank 70 whereupon constant recirculation of the liquid 40 may be maintained through the agency of the 45 return conduit 72 and the pump 74.

The carrier member 16 is mounted for rotation upon the vertically extending bearing column, 80, as shown in Figure 2, which is rigidly mounted upon the plate 82 and is in turn bolted to the transverse frame members 84 with respect to which it is preferably insulatingly supported. The rotatable carrier member has a central bearing portion 86, as well as a radially, outwardly extending portion terminating in the annular, horizontal 55 flange 88. Attention is directed to the fact that the flange 88 is positioned over the plating bath. An annular supporting plate 90 resides directly upon the top surface of the flange 88 and has its peripheral portions extending outwardly beyond 60 the said flange and provided with spaced slots 92 of the proper size to accommodate the fasteners delivered by the inclined chute member 14. An annular contact spring holder 94 overlies the supporting plate 90 and is peripherally co-extensive 65 therewith. The members 90 and 94, spaced by an annular plate 96, are fastened securely to the horizontal flange 88 by means of a plurality of machine screws 98. The annular contact spring holder 94 is peripherally cut, as shown in Figures 70 3, 9 and 10, and is provided with a plurality of contact springs 100 which are bolted thereto by means of the machine screws 102 and are positioned so that the curved end portions 104 reside directly above the slots 92.

Means is provided to individually introduce the progression of fasteners delivered by the inclined chute into supporting relationship with the peripheral slots 92 and in contacting relationship with the contact springs 100. This means comprises an ejector cam, shown in Figures 4 and 7, and having a horizontally extending arm 106 terminating at one edge in the bracket 108 which is rigidly fastened to the bar 44. A bent finger member 110 is secured to the upper surface of the arm 106. Attention is directed to the fact that the finger member 110 extends slightly inwardly beyond the ends of the spring contact fingers 100. Accordingly, rotation of the carrier, in the direction indicated by the arrow in Figure 4, causes the spring fingers to ride up the curve of the finger member 110. In this position these spring fingers will be upwardly positioned, as shown in Figure 5, and, when one of the adjacent slots 92 comes opposite the line of fasteners in the conveying chute 14, the end fastener will freely slide thereto. Upon further subsequent rotation, the spring contact finger associated with this respective slot will be released by the end of the curved finger member 110 and will immediately snap into the position shown in Figure 9.

Movement of the carrier is effected through the agency of a ratchet 112 rigidly secured thereto and driven in progressive step by step rotational movement through the agency of the spring-pressed pawl 114 which is mounted upon the arm 116. It will be noted that the arm 116 is rotatably mounted with respect to the bearing portion 86 of the carrier and is adapted to be reciprocated by means of the connecting rod 118 which is in turn pivoted at its other end to the eccentric 120 by means of a pivot which is eccentrically adjustable by any convenient means. The eccentric member is driven in a manner which will be herein-after described to cause the pawl 114 to reciprocate and repeatedly engage the ratchet for driving the carrier in step by step rotation in the direction shown in Figure 4. It will be understood, from the above disclosure, that the rotational movement produced at each step will preferably correspond to the rotational distance necessary to bring each successive slot 92 in registration with the progressive line of fasteners being supplied by the inclined chute 14 although under other preferred conditions the fasteners may be fed to the slots 92 without stopping the rotational movement of the carrier.

Attention is directed to the fact that the arm 106 of the ejector member, being positioned below the supporting plate 90, engages behind the fasteners as they complete the cycle of rotation and ejects them radially outwardly at a point directly above the deepened or well portion 62 of the plating tank from whence they drop into the bath. The ejected fasteners fall into and are caught by a removable basket or cage 122, shown in Figures 1 and 2, and which is positioned in the aforesaid well portion 62.

The current for electro-plating is conducted to fasteners which, in this instance, correspond to a cathode through the agency of a resilient spring contact member 124 mounted upon the arm 126 which is insulatingly secured to the anode member 66. The spring contact member 124 is in wiping engagement with the peripheral edge of the contact spring holder 94, as shown in Figure 6, and is connected to an appropriate source of direct current electricity. The anode assembly comprises a pair of curved conducting bars 128 mounted at the upper edges of the plu-

rality of radially spaced, U-shaped supports 130 which rest upon fibre blocks 132, as shown in detail in Figures 1 and 6. This assembly is considerably connected to the other terminal of the aforementioned source of direct current and supports a plurality of wire baskets 134 which are rigidly fastened to and supported by conducting hook members 136 having an end adapted to embrace the conductor bars 128. The wire baskets or cages 134, as is apparent from Figure 6, are provided to support the pieces of substance to be plated and to support the pieces of anode material and to continually maintain them in electrical circuit whereby to permit electro-plating of the material thereof upon the fasteners. The preferred embodiment disclosed herein for purposes of illustration, is particularly adapted for the production of articles plated with cadmium or like metal and, accordingly, the chunks of material 34 may be pieces of cadmium.

The hopper mechanism, as well as the carrier and pump, are all driven through the agency of the motor 138, the drive belt 140 and suitable pulleys which rotate the counter-shaft 142. The crank member 42 of the hopper mechanism is driven from the countershaft 142 by means of the drive fan 144 engaging with suitable fan sprockets. The pump is driven directly by means of the drive belt 146 while the drive belt 148, mounted upon suitable pulleys, rotates the eccentric 120 for reciprocating the connecting rod 118 and rotating the carrier.

In operation, the fasteners fed in the hopper and arranged in the inclined chute or conveyor 14 slide downwardly by their own weight until they reach the bottom of the chute. The continuous line of fasteners is then individually and in seriatim order arranged in the peripheral slots 92 upon the rotating carrier as it is caused to move through a step by step rotation by the agency of the aforementioned pawl and ratchet mechanism. Attention is directed to the fact that the relative positioning of the fasteners and the liquid level in the plating bath is at this time such that the portions which it is desired to electroplate are completely immersed. At this time, since the electrical circuit is completed through the spring contact 124 and the spring contact fingers 100 to the fasteners, each of these members becomes a cathode and electro-plating of the immersed portions commences. It will be appreciated that the carrier may be operated in timed relationship to the distance of rotation by control of the speed of the motor 138. Accordingly, the character of the coating produced upon the articles may be thus accurately controlled. As the fasteners have substantially completed their cycle of rotation with the carrier they are automatically ejected from the slots 92 by the member 106. It will be evident that at this time the electrical circuit is broken whereupon plating immediately ceases. When the basket or cage 122 has been filled with the plated articles, it may be removed from the well 62 by sliding it to the dotted line position shown in Figure 1, from whence it may be readily lifted upwardly and outwardly and another replaced in its stead. Preferably the portions of the carrier 14 and the end of the inclined chute or conveyor 16 which are likely to become immersed in the plating solution are given a coat of insulating varnish 150 or some other substance which is not susceptible to the passage of electric current.

The present invention provides a machine and method for rapidly and continuously plating

great numbers of articles of a carefully controlled portion of the surface thereof only and under controlled conditions of plating. Moreover, while it has been found convenient to discharge the plated articles directly into the bath at the termination of the plating step, the present invention comprehends application of any suitable mechanism for continuously removing the screws from the solution at this point.

10 It is thought that the invention and numerous of its attendant advantages will be understood from the foregoing description and it is obvious that numerous changes may be made in the form, construction and arrangement of the several parts without departing from the spirit or scope of the invention, or sacrificing any of its attendant advantages, the form herein described being a preferred embodiment for the purpose of illustrating the invention.

15 The invention is hereby claimed as follows:

20 1. A plating machine for fasteners comprising a plating bath, a carrier arranged above the bath, movable in a closed horizontal path, fastener supporting means arranged on the carrier and being located over the bath throughout the path, said bath and supporting means being connected to a source of electric current for electroplating, means to secure fasteners to the supporting means with a preselected portion only, immersed 25 in the plating bath, means to move said carrier through said path while maintaining the fasteners so immersed, and means adjacent the end of said path to release the fasteners from securement with the carrier whereby to permit the fasteners to drop into the bath, and means in the bath for receiving the fastener so released from the supporting means.

30 2. A plating machine for plating fasteners on a predetermined portion of the surface thereof only comprising a fastener feeding device, carrier means for continuously engaging said fasteners for support thereof, said carrier means being rotatable in a horizontal plane above the bath to convey the fasteners in a rotational path while maintaining them at a fixed elevational position with respect to a plating bath, an anode in said bath, said last-named means being operatively mounted with said engaging means above the bath throughout its path of travel electrical 35 means connected to said anode and said carrier for causing electro-plating of said immersed portions, means for discharging said fasteners from the carrier after plating has been completed, and means in the bath for receiving the discharged fasteners.

40 3. In a plating machine for plating fasteners, a plating bath, a rotatable carrier arranged above the bath, said carrier being mounted for rotation about a substantially vertical axis and having a plurality of fastener supporting means arranged thereon, comprising a supporting surface with a laterally facing recess therein for receiving a headed screw shank, while said supporting surface engages in supporting relationship beneath the head portion and yieldable grasping means on the supporting means extending in operative relationship to said recess, a fastener feed means positioned at a point adjacent the rotational path of travel of said carrier, means to move said carrier through said rotational path, means to continuously transfer fasteners from said feed means to the supporting means at said point comprising releasing means for said yieldable grasping means, means to automatically discharge the fasteners from the supports at another point ad-

jacent said transfer means, anode means in said bath, and electrical means connected to said anode and said yieldable grasping means whereby to supply a plating current to the fasteners when they are supported by said supporting means.

4. A plating machine for fasteners comprising a plating bath, a carrier arranged above the bath movable in a closed horizontal path, fastener supporting means arranged on the carrier and being located over the bath substantially throughout its path, means for connecting said bath and supporting means to a source of electric current for electroplating, means to secure fasteners to the supporting means with a preselected portion only immersed in the plating bath, means to move said carrier in said path while maintaining the fasteners so immersed, means adjacent the end of said path to release the fasteners from securement with the carrier, and means in the bath for receiving the fasteners so released from the supporting means, said fastener-receiving means being removable from the bath for facilitating recovery of the plated fasteners.

5. A plating machine for fasteners comprising a plating bath, a carrier arranged above the bath movable in a closed horizontal path, fastener supporting means arranged on the carrier and being located over the bath substantially throughout its path, means for connecting said bath and supporting means to a source of electric current for electroplating, means to secure fasteners to the supporting means with a preselected portion only immersed in the plating bath, means to move said carrier in said path while maintaining the fasteners so immersed, means adjacent the end of said path to release the fasteners from securement with the carrier, means in the bath for receiving the fasteners so released from the supporting means, said supporting means comprising a horizontal annular plate having an annular outer periphery, radial slots formed in said plate extending inwardly from said annular periphery, and resilient means above said recesses resiliently urged downwardly toward the plane of said plate to engage the head of a fastener disposed in said slot.

6. A plating machine for fasteners comprising a plating bath, a carrier arranged above the bath movable in a closed horizontal path, fastener supporting means arranged on the carrier and being located over the bath substantially throughout its path, means for connecting said bath and supporting means to a source of electric current for electroplating, means to secure fasteners to the supporting means with a preselected portion only immersed in the plating bath, means to move said carrier in said path while maintaining the fasteners so immersed, means adjacent the end of said path to release the fasteners from securement with the carrier, said supporting means comprising a horizontal plate having a marginal peripheral edge annularly disposed, said plate being provided with slots extending radially inwardly from said annular marginal periphery and opening radially outwardly, means on said carrier above said recesses and resiliently urged downwardly toward the plane of said plate for yieldably engaging the head of a fastener received within said slot, and fixed means at a predetermined point opposite said annular marginal periphery operative to urge said resilient means upwardly away from the plane of said plate for releasing said head portion.

7. A plating machine for fasteners comprising a plating bath, a carrier arranged above the bath

- movable in a rotational path, fastener supporting means arranged on the carrier and being located over the bath substantially throughout its path, means for connecting said bath and supporting means to a source of electric current for electro-plating, means to secure fasteners to the supporting means with a preselected portion only immersed in the plating bath, means to move said carrier in said path while maintaining the fasteners so immersed, means adjacent the end of said path to release the fasteners from securing with the carrier, said supporting means comprising a horizontal plate having a marginal peripheral edge annularly disposed coaxially with
- said rotational path, said plate being provided with slots extending radially inwardly from said annular marginal periphery and opening radially outwardly, means on said carrier above said recesses and resiliently urged downwardly toward the plane of said plate for yieldably engaging the head of a fastener received within said slot, and fixed means at a predetermined point opposite said annular marginal periphery operative to urge said resilient means upwardly away from the plane of said plate for releasing said head portion.

CARL G. OLSON.
